UNITED STATES PATENT OFFICE.

JOHN GEORGE ROBINSON, OF MANCHESTER, ENGLAND, ASSIGNOR TO SUPERHEATER CORPORATION, LIMITED, OF LONDON, ENGLAND.

STEAM-SUPERHEATER.

1,301,606.

Specification of Letters Patent. Patented Apr. 22, 1919.

Application filed October 23, 1916. Serial No. 127,280.

To all whom it may concern:

Be it known that I, JOHN GEORGE ROBINSON, a subject of the King of Great Britain and Ireland, residing at Manchester, England, (whose post-office address is "Mere Bank," Fairfield, Manchester, Lancashire, England,) have invented certain new and useful Improvements in and Relating to 5 Steam-Superheaters of the Multiple Smoke or Fire Tube Type; and I do hereby declare the following to be a full, clear, and exact description of the invention, such as will enable others skilled in the art to which it appertains to make and use the same.

10 This invention has for its object improvements in and relating to steam superheaters of the multiple smoke or fire tube type.

The invention relates more particularly to those types of superheaters in which the 15 saturated steam inlet and superheated steam outlet ends or end portions of each superheater element are bent laterally or vertically and are fixed in holes in a plate or flange block these holes extending through 20 the flange block at right angles or substantially at right angles to the axes of the smoke or fire tubes of the boiler into which the superheater elements extend and the flange block being secured to the bottom or 25 to a wall of the header lying parallel or substantially parallel with the axes of the smoke or fire tubes.

The principal object of the present invention is to provide a more efficient jointing 30 of the ends of the superheater pipes or elements to the bottom or wall of the header while at the same time providing for the easy disconnection and withdrawal of the ends of the elements from the bottom or 35 wall of the header and the easy withdrawal of the elements from the smoke tubes of the boiler. Further the construction provides 40 freer access to the fastening nuts by which the flange blocks are secured to the wall of the header. Other objects and advantages 45 attained by the several illustrated constructions according to this invention will be hereinafter set forth.

In the drawings, Figure 1 is a side view 50 of a portion of a superheater constructed according to this invention. Fig. 2 is a vertical section of one of the devices for securing the end portions of the superheater elements to the header, and is drawn to a larger

scale. Fig. 3 is a side view and a plan view 55 of the fastening block shown in Fig. 2. Fig. 4 is a plan view of a fastening block showing a modification. Fig. 5 is a sectional plan view of portions of the header and one of the boiler fire-tubes, showing the 60 fastening block of Fig. 4 and showing also a preferred form of superheater element. Figs. 6 and 7 are plan views of fastening blocks showing modifications.

The boiler is provided with a tube-plate 1 65 and fire-tubes 2, and 4 is a header secured in the smoke-box in front of the ends of the fire-tubes. This header is divided by suitable partitions 13 into chambers for superheated steam and for saturated steam. 70 An inlet 14 is provided in the header for the saturated steam, and an outlet 15 for the superheated steam. All of these parts are of any approved construction.

The superheater elements 3 are U-shaped 75 pipes which extend longitudinally in the fire-tubes. In order to connect these pipes 3 with the header, they have end portions 5 and 5^a arranged at substantially a right angle to their main portion, and the sides 80 of the header have holes 9 and 9^a for the steam. The end portions of the pipes 3 are rigidly secured in fastening blocks 6, by expanding them in holes therein by means of a tube-expander, or they are secured therein 85 in any other approved manner. The fastening blocks 6 are secured to the header by studs 8 which are permanently screwed into holes in the header side wall. The projecting portions of the studs extend through 90 holes 7 in the fastening blocks, and have fastening nuts screwed on them.

The studs are preferably arranged at the end portions of the block with the steam pipes between them, and the joint between 95 the block and the header is made steam-tight in any approved way.

The fastening blocks are arranged vertically in separate sets as shown in Fig. 1, and the studs of each set are arranged in parallel 100 horizontal planes. In order to facilitate the removal of the superheater elements from the fire-tubes, each fastening block 6 has a relatively deep slot or channel 10 formed crosswise in the side of it which bears against 105 the header wall and at the end of each stud hole 7. When a superheater element is to be removed, its fastening nuts 11 are removed,

and the fastening block is slid upon its studs until the free ends of the studs are clear of its holes 7, and are in its slots 10. The slots 10 are proportioned in depth so that the pipes 3 do not jam against the side wall of the fire-tube before the studs are clear of the holes 7, and the superheater element is removed by sliding it longitudinally when the slots 10 are free to slide laterally over the studs.

In the fastening block shown in Fig. 2 and Fig. 3 the pipes and studs are all arranged in one plane. In the modification shown in Fig. 4 the pipes and studs are arranged in 15 staggered relation.

In Fig. 5 the pipes 2 have offset parts 12 in their main portions adjacent to their end portions 5 and 5^a, and which are offset so that they project toward the header. These offset parts are preferably provided as they will afford more space and will also spring a little, and will permit the disengagement of the blocks 6 from the studs with more clearance before the pipes jam in the fire-tubes. This construction also permits the fastening blocks to be made of liberal thickness, which is desirable.

The superheater element nearest the tube plate of the boiler is removed and replaced by sliding its block 6 over all the studs of the set to which it pertains, and the slots 10 are therefore formed to extend clear across the fastening blocks.

In the modification shown in Fig. 6 the studs 8 are arranged in a plane midway between the steam pipes; and in the modification shown in Fig. 7 one fastening block is shown connected to two superheater ele-

ments, instead of to one element as shown in Fig. 7.

What I claim is:

1. In a superheater, a header provided with holes for steam in its side wall, superheater elements having their end portions arranged at an angle to their main portions, 45 screwthreaded studs which project from the side wall of the header, fastening blocks secured to the end portions of the superheater elements and provided with holes for engaging with the said studs, said blocks having 50 also slots or channels formed crosswise in them at the ends of their stud holes and slideable laterally over the studs, and nuts on the studs for securing the blocks to the header.

2. In a superheater, a header provided 55 with holes for steam in its side wall, superheater elements having their end portions arranged at an angle to their main portions and having offset parts in their main portions adjacent to their said end portions and 60 projecting toward the header, screwthreaded studs which project from the side wall of the header, fastening blocks secured to the end portions of the superheater elements and provided with holes for engaging with the 65 said studs, said blocks having also slots or channels formed crosswise in them at the ends of their stud holes and slideable laterally over the studs, and nuts on the studs for securing the blocks to the header.

In testimony whereof I have affixed my signature in presence of two witnesses.

JOHN GEORGE ROBINSON.

Witnesses:

W. H. SINSON,
WESTALL H. BARKER.
